(57) **CLAIM**

We claim the ornamental design for a motorcycle seat component, as shown and described.

DESCRIPTION

FIG. 1 is a top, front, left perspective view of a motorcycle seat component embodying our new design;

FIG. 2 is a top, rear, right perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the motorcycle seat component that form no part of the claimed design.
